UNITED STATES PATENT OFFICE.

HENRY J. CASANOVA, OF CHICAGO, ILLINOIS.

FRAME CONSTRUCTION.

995,437.

Specification of Letters Patent. Patented June 20, 1911.

Application filed August 9, 1910. Serial No. 576,416.

To all whom it may concern:

Be it known that I, HENRY J. CASANOVA, residing at Chicago, in the county of Cook and State of Illinois, have invented certain new and useful Improvements in Frame Construction, of which the following is a specification.

The invention relates in general to frame construction adapted to be used for all purposes where a light frame-work is desired, and particularly adapted for the frame-work in flying machines of all types.

The invention resides primarily in the means for securing two pieces of material together, as part of the frame-work, consisting of tie rods and bars, the former being capable of resisting tensional strains so as to prevent the separation of the frame-work, and the latter being capable of resisting compression strains to prevent the collapsing of the framework.

Further advantages of my invention will more fully appear in the specification, and some of the manners in which the invention may be employed are shown in the accompanying drawing, in which—

Figure 1 is a side elevational view of my improved frame construction, Fig. 2 is a sectional view on the section line 2—2, of Fig. 1, Fig. 3 is an enlarged detail sectional view, and Figs. 4, 5, 6 and 7 are similar views to Fig. 1, showing modifications of frame-work to which my invention may be applied.

Referring now more particularly to the drawing, and specifically to Fig. 1, a bamboo frame 10 serves as the body portion of the frame with curved pieces of material 11 secured thereto, to either one of which may be attached a suitable material. The curved frame members 11 are secured to the bar 10 by means of suitable tie rods 12 which are preferably made of steel, passing through both the frame members 10 and 11 and held thereto by means of suitable nuts 13 and washers 14. It is of course understood that as many tie rods may be employed as are deemed necessary for proper construction work. A tubular bar 15, through which the tie rods 12 pass, is interposed between curved member 11 and the bar 10, the ends of such bars 15 either bearing directly upon opposing surfaces of the framework, or such ends may bear upon the washers 14 or suitable block members (not shown).

The frame-work of the construction referred to herein and shown is subjected, primarily, to two strains, one of which tends to separate the frame members 11 from the frame member 10, which is resisted by means of the tie rods 12, which have great tensional strength. Collapsing of the frame members toward each other is prevented by the bars 15 which have greater compression strength than the tie rods 12, and such bars also serve to prevent the tie rods from buckling.

In Figs. 4, 5, and 7 modified forms of frame construction are shown, all of which embody the invention as described in connection with Fig. 1, except in Fig. 5 plates 16 are interposed between the ends of the bars 15 and the frame work, and metal clips 17 are used in place of the washers 14, which give additional strength to the frame members if made of wood or other fibrous material.

In my preferred form of construction the frame work is made of bamboo or other light woods, the tie rods being made of steel and the bars 15 of aluminum. It is also desired that the corner pieces 18, washers 14, plates 16 and clamps 17 be also made of aluminum. The main bars 10 of the frame constructions shown in Figs. 4 and 5 may be of any suitable light material, and the main bar 10 of Fig. 7 is of bamboo, as shown in Fig. 1.

In Fig. 6 a slightly modified form of construction is shown for securing two parts of a frame-work at right angles to each other. The tie rods 12 and the bar members 15 are employed in this construction, but as both of the frame members 10 shown in this figure are of bamboo a plug 19 is placed at one end of the frame 10 which abuts against the other part of the frame, and the tie rod 20 passes through said plug and through the frame 10 for preventing lateral displacement of one member relative to the other. The ferrule 21 surrounds the end of the frame 10 adjacent the plug 19 to prevent the breaking away of the side walls of the frame.

It is obvious that a great many different forms of frames may be constructed wherein my invention is applicable, and therefore without confining myself to the particular constructions herein shown I claim:

A frame construction for aerial vessels comprising two frame members suitably

spaced apart, hollow metal tubes interposed between said frame members and having their ends abutting against said frames, metal washers interposed between the ends of the tubes and the frame members, light wire tie rods extending through said tubes, washers and frame members, washers on the outer ends of said tie rods and nuts for drawing said frames, tubes and washers together.

HENRY J. CASANOVA.
